[57] CLAIM

The ornamental design for two fluid press-feeding pump, substantially as shown and described.

DESCRIPTION

FIG. 1 is a perspective view of a two fluid press-feeding pump of my new design;

FIG. 2 is a front elevational view thereof;

FIG. 3 is a side elevational view thereof taken from the left-hand side of FIG. 2;

FIG. 4 is a rear elevational view thereof;

FIG. 5 is a top plan view thereof;

FIG. 6 is a bottom plan view thereof;

FIG. 7 is a side elevational view thereof taken from the right-hand side of FIG. 2; and

FIG. 8 is a perspective view of the state where a static mixer is inserted in the mixer cover of the two fluid press-feeding pump.
